US00D677548S

(12) **United States Design Patent**
Rosenau et al.

(10) **Patent No.:** **US D677,548 S**
(45) **Date of Patent:** **** Mar. 12, 2013**

(54) **DUST EXTRACTOR**

(75) Inventors: **Isabell Rosenau**, Frankfurt am Main (DE); **Alexander Foerster**, Wiesbaden (DE); **Norbert Hahn**, Hunstetten-Limbach (DE); **Stefan Sell**, Mainz (DE)

(73) Assignee: **Black & Decker Inc.**, Newark, DE (US)

(**) Term: **14 Years**

(21) Appl. No.: **29/396,870**

(22) Filed: **Jul. 8, 2011**

(30) **Foreign Application Priority Data**

Jan. 12, 2011 (EM) 001254338-0001

(51) **LOC (9) Cl.** **08-01**

(52) **U.S. Cl.** **D8/70**

(58) **Field of Classification Search** D32/3-33, D32/182; D23/213; 408/67, 56, 58-61; D8/70, 61, 69, 80, 105, 499; D15/138; 173/198; 454/49, 66; 144/252.1; 451/453, 456

See application file for complete search history.

(57) **CLAIM**

The ornamental design for a dust extractor, as shown and described.

DESCRIPTION

FIG. 1 is a front perspective view of a dust extractor showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines in the figures illustrate features that form no part of the claimed design.

1 Claim, 8 Drawing Sheets
